US0D1048791S

(12) **United States Design Patent** (10) Patent No.: **US D1,048,791 S**
(45) Date of Patent: ** Oct. 29, 2024

(54) **WATER PURIFICATION FILTRATION AND HEATING DISPENSER**

(71) Applicant: **STRAUSS WATER LTD**, Or Yehuda (IL)

(72) Inventors: **Idan Adi Orbach**, Rosh Ha'Ain (IL); **Maya Ben David**, Givat Ada (IL)

(73) Assignee: **STRAUSS WATER LTD.**, Or Yehuda (IL)

(**) Term: **15 Years**

(21) Appl. No.: **35/519,116**

(22) Filed: **Nov. 1, 2023**

(80) **Hague Agreement Data**

Int. Filing Date: **Nov. 1, 2023**

Int. Reg. No.: **DM/233156**

Int. Reg. Date: **Nov. 1, 2023**

Int. Reg. Pub. Date: **Nov. 24, 2023**

(51) **LOC (14) Cl.** 07-01

(52) **U.S. Cl.**

USPC **D7/307**

(58) **Field of Classification Search**

(57) **CLAIM**

The ornamental design for water purification filtration and heating dispenser as shown and described.

DESCRIPTION

1. Water purification, filtration, and heating dispenser
  - 1.1 Perspective view with trays folded
  - 1.2 Front view with both trays folded
  - 1.3 Back
  - 1.4 Left view with both trays folded
  - 1.5 Right view with both trays folded
  - 1.6 Top view with both trays folded
  - 1.7 Bottom view with both trays folded
  - 1.8 Bottom and back perspective view with both trays folded
  - 1.9 Perspective view with left tray opened
  - 1.10 Perspective view with right tray opened
  - 1.11 Perspective view with both trays opened
- The parts colored in white and delineated in broken lines form no part of the claimed design.

1 Claim, 11 Drawing Sheets
